UNITED STATES PATENT OFFICE.

JOSEPH LINDEMAN, OF NEW YORK, N. Y.

PLASTIC PILE.

1,346,222.

Specification of Letters Patent. Patented July 13, 1920.

Application filed April 30, 1917. Serial No. 165,451.

To all whom it may concern:

Be it known that I, JOSEPH LINDEMAN, a citizen of the United States, residing at New York city, in the county of New York, State of New York, have invented certain new and useful Improvements in Plastic Piles; and I do hereby declare the following to be a full, clear, and exact description of the invention, such as will enable others skilled in the art to which it appertains to make and use the same.

The present invention is directed to improvements in concrete piles, and has for its object to provide a device of this character which can be driven into the river bed without the danger of cracking the cement body when being driven.

A further object of the invention is to provide a concrete pile having reinforcing elements of novel form embedded therein so as to strengthen the same.

A still further object of the invention is to provide a pile of this character so constructed that the same can be conveniently molded into the form, and further to provide novel means for arranging the reinforcing elements previous to the application of the cement body thereto.

With these and other objects in view, this invention resides in the novel features of construction, formation, combination and arrangement of parts to be hereinafter more fully described, claimed and illustrated in the accompanying drawing, in which:

Figure 1 is a side elevation of the complete pile.

Fig. 2 is a longitudinal sectional view through the mold.

Fig. 3 is a sectional view on line 3-3 of Fig. 2.

Fig. 4 is a sectional view on line 4-4 of Fig. 2.

Fig. 5 is a side view of the preferred form of mold.

Referring to the drawing 1 indicates the dolly of the pile, said dolly being formed from wood and has its lower end provided with an extension 2, whereby the annular shoulder 3 is provided, said dolly being further provided with an annular shoulder 4 the purpose of which will appear later.

A ring 5 is employed and receives the extension 2, said ring having its under surface provided with a circular series of eyes

6. A metallic band 7 is engaged around the ring 5 and adjacent part of the dolly 1 and has its upper edge engaged with the shoulder 4, said ring serving to prevent the band and dolly from splitting when subjected to blows during the driving of the pile.

The tapered point 8 is provided, and is preferably formed from metal, but if desired it can be formed from wood as are the dolly and ring 5. The point has a circular series 65 of eyes 9.

Between the ends of the pile are several rings 11, each having eyes 12 as best seen in Fig. 3. The end elements are connected by a metal reinforce 10, preferably a single 70 length of wire rove through their various eyes so as to form two sets of strands—one an outer shell or cage wherein all strands are longitudinal and substantially parallel, and the other an inner core where- 75 in all strands converge to the axis of the structure near its midlength and there cross each other. The strands in the outer set preferably pass through the eyes of the rings. If a single wire is used as suggested, 80 it can be attached to one end eye as 6, led straight down through several ring-eyes 12 to the corresponding end eye 9, then led up and diagonally across to an upper eye 6 about opposite the first eye, then again 85 straight down, and so on—thus making the successive stretches of the wire alternately constitute strands in the two sets. However, this can well be left to the user, as he may prefer to employ separate lengths for 90 the two sets of reinforcing elements.

After the reinforce has been properly arranged the dolly 1 is removed so that the cement in liquid form can be poured through the opening of the ring 5, after which it 95 hardens and firmly embeds therein the reinforcing element. The strands are held against distortion when the cement is poured in the mold by the rings, 11, which are provided with eyes 12 for engaging the strands. 100 It will be of course understood that after the strands have been properly connected with the dolly and point that this skeleton formation is placed in a suitable mold so that the strands and rings will be embedded in the cement and out of sight the mold being removed before the pile is driven.

From the foregoing description it will be seen that a pile has been provided which is particularly adapted for use in connec- 110

tion with docks, wharfs or the like, or in any place where it is desired to use a pile which will last indefinitely.

The preferable form of mold 13 is shown in Fig. 5, and consists of hingedly connected sections 14, said sections having their free edges provided with longitudinal flanges 15, one of which has pivotally connected thereto a latch 16 which is operable to hold the flanges in clamped engagement and the sections in confronting relation. The sections of the mold are so shaped as to produce a tapered pile, and are provided with wooden linings 17 so the cement will dry more quickly.

What is claimed is:—

A pile including spaced end elements, circular series of eyes on the inner faces thereof, a plurality of rings arranged in spaced

relation to each other between the end elements, each ring being formed with eyes arranged in a series therearound, and a reinforcing strand rove through the eyes on the end elements and rings to provide a shell of longitudinal stretches, and led from each end eye across to an eye substantially opposite at the other end to form diagonal stretches so disposed as to cross each other substantially at the midlength of the pile; and a plastic filling inclosing all stretches and rings.

In testimony whereof, I affix my signature, in the presence of two witnesses.

JOSEPH LINDEMAN.
